UNITED STATES PATENT OFFICE.

HERMAN D. PALMER AND JOHN W. BRHEL, OF HARTFORD, WISCONSIN, ASSIGNORS TO THE KISSEL MOTOR CAR COMPANY, OF HARTFORD, WISCONSIN, A CORPORATION OF WISCONSIN.

APPARATUS FOR MEASURING MATERIALS IN CONCRETE CONSTRUCTION.

Application filed October 17, 1921. Serial No. 508,409.

To all whom it may concern:

- Be it known that we, HERMAN D. PALMER, a citizen of Germany, and JOHN W. BRHEL, a citizen of the United States, both residing 5 at Hartford, in the county of Washington and State of Wisconsin, have invented an Improved Apparatus for Measuring Materials in Concrete Construction, of which the following is a specification.
- 10 The invention has reference to an improved method of measuring the materials constituting the elements of concrete mixture, commonly termed "the mix", which is especially adapted for use where large quantities of these materials are employed, as 15 for example, in the construction of concrete roads.
- Prior to the invention herein, it has been the custom to discharge the sand and gravel 20 to be mixed directly from the bins containing the same into the compartments of a truck body or wagon box by means of which they are conveyed to the scene of the building operation, for mixture with the 25 cement to form the concrete. By this method the amount of the material discharge from a sand or gravel bin is controlled by an attendant stationed at or near the bin, upon signal from another attendant located in 30 the vehicle body, the latter determining by sight when the proper amount of material has been discharged. Obviously it is of extreme importance that the proportions of the elements of the mix be accurately and 35 uniformly maintained, and to insure against inaccuracy in this respect it is customary for the state to employ inspectors at the place of loading. Frequently the attendants make miscalculations, with the result 40 that material must be removed from the vehicle body or added thereto. Consequently the loading operation consumes a substantial amount of time; there is a considerable waste of materials due to the removal of 45 the excess in a given case and depositing the same on the ground at the side of the vehicle body; and an excessive number of men are employed to accomplish the measuring and discharging operation.
- 50 The present invention consists in the provision of an apparatus by means of which the measurement and discharge of the sand and gravel, and, if desired, the cement, is controlled in each instance by a single at-

tendant, and is effected in such a way that 55 a high degree of accuracy is insured; the principal aim of the invention being to simplify the operation and thus to minimize the cost thereof, by eliminating waste in labor and materials, minimizing the amount 60 of time required for the operation, and otherwise increasing the efficiency thereof.

An important object of the invention is to provide an apparatus of a simplified construction which lends itself readily to the 65 change from time to time, as may be necessary, of the place of loading.

The objects of the invention thus generally stated, together with other and ancillary advantages, are attained by the construction and arrangement illustrated in the accompanying drawings forming part hereof wherein we have illustrated a preferred form of the invention. It is to be understood, however, that the invention is not 75 limited to the precise construction and arrangement herein disclosed for it will be obvious that various changes may be made without departing from the spirit and scope of the invention as expressed in the ap- 80 pended claims.

Figure 1 of the drawings is a front elevation of our improved apparatus illustrated in connection with a bin containing sand and gravel. Fig. 1^a is a diagrammatic view 85 showing gravel, sand and cement measuring and loading stations. Figs. 2 and 3 are respectively end and side views on an enlarged scale of the upper portion of one of the loading stations.

We have herein shown our invention employed in connection with a bin previously constructed. Thus, referring to Fig. 1, A designates generally a bin having a central partition B forming two compartments A' 95 and A². The compartment A' herein constitutes the sand compartment and the compartment A² the gravel or stone compartment. As will be understood, the sand and gravel is introduced into the compartments 100 A' and A² respectively by suitable means such as an endless conveyor (not shown).

Stationed opposite each of the compartments A' and A² we provide what may be termed generally as loading stations C and 105 C'. Each of these stations comprises a framework 10 constituting a sub-structure supporting a plurality of measuring units

in the form of boxes 11 or 11' at a substantial height above the ground. The framework is arranged so as to permit the passage therethrough of a truck or other vehicle D beneath the boxes, and the members constituting the framework are connected by means of bolts 10^a in such a way as to permit the easy assembling and disassembling of the same as it becomes necessary to shift the place of loading from time to time. Upon the top of the framework adjacent the measuring boxes there is provided a platform 12 for an attendant and leading downwardly from outlets provided in the respective compartments A' and A² are discharge troughs E which are controlled by suitable valves F. At the lower end of each of the troughs E there is provided a swingable spout 13 suitably mounted upon the lower end of the trough E so as to be swingable, as by means of a handle 13^a laterally over the various measuring boxes 11 or 11'. Herein we employ three such measuring boxes.

25 Suitable operating means for the valve F extends to a point adjacent the platform 12 within convenient reach of the attendant stationed thereon, whereby he may control the flow of the material into the measuring boxes. Such valve operating mechanism may comprise a lever 14 mounted on the spout 13 and operatively connected by means of a cable 15 with the valve F whereby the attendant may readily control the flow of sand or gravel as the case may be from the bin. Obviously the discharge spout 13 is swung successively from a position over one measuring box to the next until all of the boxes have been filled.

40 When the boxes have thus been filled, the attendant awaits the positioning of the vehicle body below the station C or C' under the boxes 11 or 11' whereupon he effects the discharge of the measured material into the vehicle body. The latter is divided into a number of compartments corresponding to the number of measuring boxes at each station, by means of swinging partition members D'. Suitable means designated 50 generally at D², is employed for releasably holding these partition members in position so that the material in the various compartments may be separately discharged.

The means whereby the attendant controls the discharge of the material into the vehicle body comprises preferably, a plurality of hinged doors 16 (Fig. 3) one for each of the measuring boxes. These doors constitute releasable bottoms for the 60 boxes and are adapted for simultaneous operation under the control of a retaining means operable by means of a hand lever 17. Each of the doors 16 is pivotally mounted upon a rod 18, to one end of which is fixed an arm 19 pivotally connected at its

opposite end to a bar 20 carrying counterweights 21 at each end thereof. The doors are normally locked in their closed position by means of a pair of trip bars 22 pivotally connected with each of the doors by means 70 of a link 23, and mounted for up and down movement. These bars are located at opposite sides of the framework and each is mounted upon a pair of swinging arms 24, one at each end thereof and inclined somewhat forwardly so that the bar has a tendency to move forwardly and downwardly under the weight of the material contained in the boxes.

Normally the forward movement of the 80 bars 22 is prevented by means of locking means comprising retaining members 25 fast upon a rod 26 in the framework and pivoting at their free ends studs 27 adapted to engage with the forward ends of the 85 bars 22. Said ends, it will be observed, swing through an arc of a circle in the movement of the doors. The lever 17 is fixed upon the rod 26, so that when the lever is drawn forwardly by the attendant, 90 the bar 22 is free to swing forwardly and downwardly under the action of gravity. In this movement the doors 16 are permitted to drop, thereby effecting the simultaneous discharge of the material in the several 95 boxes into the compartments of the vehicle body. Preferably counterweights 28 (Fig. 2) are connected by means of chains 29 operating over idler pulleys 30, with the bars 22 to assist the weights 21 in restoring the 100 doors 16 to their closed position after the discharging operation.

The loading stations C and C' for the sand and gravel, respectively, are substantially identical except that the shape of 105 the measuring boxes in each instance is somewhat different, being designed in accordance with the character of the material measured thereby, to effect its free discharge.

In addition to the stations C and C', a station C² (Fig. 1^a) for cement may be provided. In this instance the construction is substantially identical with that of the stations C and C' except that the cement instead of being discharged from a bin into the measuring boxes may be conveyed in bags to the platform of the station, as by means of an endless conveyer 33, where they are emptied by the attendant into the boxes 110 subject to release when a vehicle is stationed therebeneath.

In the use of our improved system, as herein shown, the vehicle D is first driven into the station C' and positioned so that the several compartments of the vehicle body are respectively located below a measuring box or unit 11'. Previously the attendant upon the platform 12 has filled these boxes with gravel through the operation of the 115

lever 14, effecting the flow of material from the bin A² through the discharge trough E and swinging spout 13. The vehicle body having been positioned below the boxes 11, the attendant operates the lever 17, releasing the bar 22 for downward movement under the action of gravity acting upon the door 16. It sometimes happens that an initial movement is necessary to be imparted to the bar 22 by the attendant, and this may be accomplished through the medium of an upright handle 31 fixed upon the forward end of the trip bar 22 as shown in Fig. 3. Upon such operation of the lever 17, the stud 27 is moved out of retaining position and the bar 22 swinging on the arms 24 permits the door 16, through the medium of the links 23 to descend into open position. Upon the release of the material from the measuring boxes the counterweights 21 and 28 retract the doors 16 and the operator returns the lever to its holding position as determined by a stop pin 32.

The vehicle now proceeds to the next filling or loading station C, and receives in each of the several compartments a predetermined quantity of sand as determined by the size of the measuring boxes of this station, the operation being substantially the same and under the control of a single attendant as in the case of the gravel-loading station. Each of the compartments of the vehicle body having now received a definite quantity of gravel and sand, the vehicle may proceed to the scene of the building operation where the mixture with cement to form the concrete is completed.

If it should be desired, the mix may be completed at this stage of the operation by adding cement in measured quantities to the sand and gravel in the several compartments of the vehicle. In this case, the vehicle proceeds to the filling station C², where cement contained in the measuring boxes 11² is released for discharge into the several compartments of the vehicle.

Obviously we have provided a measuring and discharging system for the materials of the mix which materially increases the efficiency of this portion of the work. The time within which the loading is accomplished is substantially reduced, requiring on an average, five or six seconds, as compared to as many minutes with the previous method. Moreover, the operation is accomplished with much greater accuracy; with the substantial elimination of waste of material; and the number of attendants is materially reduced. The construction of the apparatus is comparatively simple and is readily adapted to meet the peculiar conditions under which it is used.

We claim as our invention:

1. In an apparatus of the character described, the combination of a supporting

structure having a plurality of measuring units, a plurality of hinged counterbalanced doors normally closing the lower ends of said units, means for locking said doors in closed position, and means for releasing the doors for effecting the discharge of the material from said units into separate compartments of a vehicle body positioned there beneath.

2. In an apparatus of the character described, the combination of an elevated support, a plurality of measuring units carried by said support and each having a drop bottom, means normally maintaining said drop bottoms in closed position, and means operable to release simultaneously said bottoms for effecting the discharge of the material from the units into a vehicle body located beneath them.

3. In an apparatus of the character described, the combination of an elevated support, a plurality of measuring boxes carried by said support and each having a drop bottom, means operatively connecting the bottoms of each of said boxes for movement in unison, means tending to hold said bottoms in closed position including a trip bar operatively connected with each of said bottoms and mounted for movement to permit the swinging of said bottoms into open position, and releasable means normally holding said bar against movement.

4. In an apparatus of the character described, the combination of a plurality of measuring units each having a hinged door constituting a bottom, a bar operatively connected with each of said doors and movable to permit the latter to swing into open position, means normally holding said bar against movement, and means for returning the doors to their closed position upon the discharge of the material in said measuring units.

5. In an apparatus of the character described, the combination of a measuring unit, a member normally closing the lower end of said unit, a bar having an operative connection with said member and mounted for movement to permit said member to move into open position, releasable means for holding said bar against movement, and means automatically returning said member to its closed position upon the discharge of the material in said unit.

6. The combination of a measuring box having a releasable bottom, a member mounted for up and down movement and operatively connected with said bottom, and means for holding said member in its elevated position whereby normally to maintain said bottom in its closed position.

7. The combination of a measuring box, a hinged door normally constituting a closure for the lower end of said box, a bar operatively connected with said door, and

means adapted to support said bar comprising a pair of links swingable to effect the raising and lowering movement of the bar with one end of the bar traveling in the 5 arc of a circle, and a locking member normally abutting said end of the bar to hold it against movement and thereby said door in its closed position.

8. The combination of a measuring box, a 10 door hinged at the lower end of said box and normally constituting a closure therefor, means normally supporting said door in its closed position but permitting of its movement into open position, and means for re- 15 turning the door to its closed position comprising an arm fixed with reference to the door and a counterbalancing weight carried by said arm.

9. In an apparatus of the character de- 20 scribed, the combination of a plurality of measuring boxes each having a releasable bottom, a bar swingably mounted for up and down movement and operatively connected with each of said bottoms whereby they are 25 opened and closed simultaneously, means for moving said bar in the direction to open said bottoms, and means operatively connected with the bar to return the doors to their initial or closed position.

30 10. The combination in an apparatus of the character described of a movable spout communicating with a material containing bin, a plurality of measuring boxes mounted forwardly of said bin and into which said 35 spout is adapted to discharge the material to be measured, means normally closing the lower ends of said boxes, means normally holding said closing means in operative or closed position, and means for releasing the 40 last-mentioned means to permit the operation of the closing means into open position.

45 11. A loading apparatus for concrete road or like construction, comprising separate stations for the sand, gravel and cement to constitute the mix, each station having one or

more units in which a preliminary measurement of the given material may be effected, and also means whereby the measured material may be discharged at the proper time into a vehicle positioned below the units. 50

12. An apparatus for measuring materials for use in concrete construction work comprising, in combination with a source of supply for the several materials to comprise the mix, a plurality of separate measuring boxes one for each of said materials, means for supporting said boxes in elevated position so as to provide a passageway beneath the boxes for a motor vehicle or the like, means for controlling the flow of the several materials by gravity directly from their respective sources of supply into said boxes and in quantities determined by the individual natures of such materials and their proportion in the mix, and means for controlling the discharge of the materials from said box into the vehicle body when the latter has been positioned to receive the materials. 60

13. An apparatus for measuring a material to be used in concrete construction work comprising, in combination with a bin having an outlet located a substantial distance above the ground, a supporting structure having a measuring box supported thereby in elevated position but below said bin outlet so as to be adapted to receive the material flowing by gravity directly from the bin into the upper open end of the box, manually operable means for controlling the flow of a predetermined quantity of the material into 70 said box to measure it, and means for controlling the discharge of the material from the box into a vehicle body positioned beneath it, said supporting structure being adapted to permit the passage of a vehicle 75 beneath the box.

In testimony whereof we have hereunto set our hands.

HERMAN D. PALMER.
JOHN W. BRHEL.
